UNITED STATES PATENT OFFICE.

CHARLES E. WAREAM, OF CINCINNATI, OHIO, ASSIGNEE TO THE AMERICAN LAUNDRY MACHINERY COMPANY, OF NORWOOD, OHIO, A CORPORATION OF OHIO.

COLLAR IRONER.

Application filed December 2, 1920. Serial No. 427,767.

This invention relates to ironing machines and more especially to that class of ironing machines used in ironing small flat articles on one side of which may be desirable to produce a high finished or polished surface, such as collars and cuffs.

The objects of the invention are to provide an improved ironing machine in which small articles may be ironed in flat form without any necessity of providing devices for stripping them from the padded rolls; to preliminarily iron the articles before they reach the main chest portion of the machine; to provide an improved relative arrangement of padded rolls and ironing chest in which the rolls and chest have relative reciprocating motion in the direction of travel of the articles between them, and more specifically in which the chest reciprocates, all for the purpose of avoiding deposits of starch on the chest; to simplify and improve the arrangement of the driving gears for the rolls so as to maintain said gears in true meshing relation and at the same time permit the rolls to be raised from the chest to avoid burning or injuring the padding; to provide means for adjusting some of the rolls independently of the others for the purpose of reducing the pressure of the earlier rolls of the train, thereby securing a relatively thicker product; to provide an improved ironing machine which is capable of producing a high finish or burnished surface upon the inner surface of the band and outer surface of the lap; to simplify and improve the manner of applying and removing the padding from the padded rolls; and finally to provide a more simple arrangement for raising the padded rolls from the chest and producing relative movement of the padded and ironing or burnishing rollers.

Further objects of the invention are in part obvious and in part will appear more in detail hereinafter.

In the drawings, Fig. 1 is an outside elevation of the left hand side of a machine embodying the invention, the driving pulley being omitted and parts of the gear casing being sectioned to expose the driving gearing; Fig. 2 is a longitudinal sectional elevation on substantially the line 2—2, Fig. 5; Fig. 3 is a similar section on substantially the line 3—3, Fig. 5; Fig. 4 is an outside elevation of the right hand side of the ma-

chine; Fig. 5 is a plan view; Fig. 6 is a longitudinal sectional elevation on the line 6—6, Fig. 5; Fig. 7 is a sectional plan view on substantially the line 7—7, Figs. 1 and 2; Fig. 8 is a detail longitudinal sectional elevation on the line 8—8, Figs. 5 and 7; Fig. 9 is a transverse sectional elevation on the line 9—9, Fig. 5; Fig. 10 in a longitudinal sectional elevation of a part of the machine on the line 10—10, Fig. 5; Fig. 11 is a detail sectional plan view of one end portion of the preliminary ironing rolls and showing the doffer knife arrangement, the view being taken on substantially the line 11—11, Fig. 10; Fig. 12 is a detail sectional plan view on substantially the line 12—12, Fig. 10, showing the pressure arms for the first and second padded roll bearings; Fig. 13 is a detail section on substantially the line 13—13, Fig. 10; Fig. 14 is a longitudinal sectional elevation on the line 14—14, Fig. 9; Fig. 15 is a detail transverse section through one of the hot rolls on the line 15—15, Fig. 5; Fig. 16 is a detail sectional elevation on the line 16—16, Fig. 5 showing the pressure cam mechanism for adjusting the first and second padded rolls relative to the chest; Fig. 17 is a detail transverse section on the line 17—17, Fig. 5, showing the pressure indicator; Fig. 18 is a transverse sectional elevation on the line 18—18, Figs. 1 and 2; Fig. 19 is a longitudinal sectional elevation of the burnishing devices on the line 19—19, Fig. 18; Fig. 20 is a detail sectional view on the line 20—20, Fig. 18; Fig. 21 is a detail sectional plan view on the line 21—21, Fig. 18; Fig. 22 is a detail sectional elevation on the line 22—22, Fig. 19, and Fig. 23 is a detail view, half in elevation and half in section, illustrating a hand operated clutch for coupling or uncoupling the padded rolls to their drive shafts.

The machine shown in the drawings comprises a suitable frame including right and left side frame members 1, 2 suitably connected together by cross ties and carrying the necessary brackets and supports for the mechanism. In said machine are mounted a series of ironing members to the operation of which the articles to be ironed are subjected during their travel through the machine. Referring to Fig. 6, these ironing members comprise a hot roll 3 and co-operating padded roll 4 at the feeding end of the

machine and which produce a preliminary ironing effect, the hot roll 3 engaging the upper surface of the article, such as the inner surface of the flap and outer surface of the band of a roll or turn-down collar. Next in order are a hot roll 5 and co-operating padded roll 6 reversely arranged relative to rolls 3 and 4 so that the hot roll 5 engages the lower surface of the article. 10 Next in order are a heated platen or support 7 having a smooth upper ironing surface and above which is located a series of padded rollers 8, all rotating in the clockwise direction and adapted to advance the articles over the surface of the ironing chest. The chest has horizontal reciprocating motion longitudinally of the machine in a manner to be described for assisting in the ironing operation and particularly for avoiding deposits 20 of starch on the chest, while the padded rolls 8 may progressively increase in diameter from the first to the last of said rolls, or from the right to the left in Fig. 6 so that the peripheral speed of each roll is slightly greater than that of the preceding roll, which tends to stretch the collar or articles being ironed and keep them smooth and flat and free from wrinkles. Beyond the chest and co-operating padded rollers is an upper padded roller 9 beneath which are a pair of burnishing rollers 10 designed to produce a high finish, if desired, upon the outer surface of the flap and inner surface of the band, or in other words, upon the lower surface of the article being ironed. 30

The machine may be driven in any suitable manner, such as by an individual electric motor, but is shown as provided with a loose belt pulley 11 on the driving shaft 12 capable of being connected thereto when desired by a suitable clutch 13 actuated by a cone 14, the shifting form 15 for which is pivoted on a stud 16 having an arm 17 connected by a link 18 to a bell crank lever 19 (Fig. 5). Bell crank lever 19 is connected by a rod 20 (Fig. 1), bell crank 21 and rod 22 to an operating handle 23 at the feeding end of the machine, enabling the operator without leaving his position at the feeding end to start and stop the machine when desired. The driving shaft 12 is provided with a worm 24 driving a worm wheel 25 on a shaft 26 extending longitudinally of the machine along its left hand frame. This shaft is provided with three bevel gears, marked 27, 28 and 29 and with one worm gear 30. Bevel gears 27 and 28 actuate the padded rolls 8. Bevel gear 29 actuates the padded rolls 4 and 6. Worm gear 30 actuates the mechanism for reciprocating the chest. 50

The several padded rolls 8 (with two exceptions to be later described) are alike as to arrangement and manner of operation. Referring to Figs. 9 and 10, each of said

rolls is journaled at its opposite ends in the arms of a pressure bearing member 31, two of said rolls being journaled in each pressure bearing member. Each two adjacent pressure bearing members are connected to links 32 which are pivoted on the right hand side of the machine on short stub shafts 33, and at the left side of the machine on the inner ends of the stub shafts 34 (Fig. 9) which at their outer ends are provided with bevel gears 35 meshing with and driven by the gears 27, 28 before referred to. On the shafts 34 are also located pinions 36, each of which drives a pair of intermediate gears 37, each of which drives two pinions 38, there being eight pinions 38 in all, one for each of the padded rolls. Each pinion 38 is loosely rotatable upon the shaft of its roll and may be coupled thereto or uncoupled therefrom by longitudinal sliding movement 85 of the clutch members 39, Fig. 5, 9 and 23. Said clutch members are like the clutch member 125 hereinafter referred to and shown in Figs. 18 and 21. They are splined to the roller shafts and are coupled to drive the rollers during the ordinary operation of the machine. However, whenever it is necessary to change or renew the padding upon a roller its clutch 39 can be uncoupled so that the roll will become freely rotatable, thereby enabling the padding to be readily unwound from the roll. By then attaching a new sheet of padding and coupling the clutch 39 the roll can be driven and the padding wound upon the roll until it is 100 built up to the proper thickness.

Intermediate gears 37 are journaled upon the pivots connecting the pressure bearing members 31 and the links 32, as a consequence of which the several gears remain in 105 true meshing relation under all circumstances, while at the same time the rollers 8 are flexible as to position and can be adjusted vertically relative to the chest. They are also self-accommodating to the 110 chest and are held against the same to produce the ironing pressure by mechanism to be later described.

The third bevel gear 29 on shaft 26 drives a bevel gear 40 on a hot roll drive shaft 41. 115 This shaft extends transversely across the machine and is the source of power for the padded rollers 4 and 6 and the co-operating heated ironing rollers 3 and 5. These latter rolls 3 and 5 are stationary or non-adjustable, although they rotate, while the padded rollers are suitably mounted to be adjustable relatively to the heated rollers to avoid burning or injuring the padding when the machine is idle. 120

On the left hand end of the machine the shaft 41 is provided with a gear 42 driving an intermediate gear 43 journaled in a lever 44 and which intermediate pinion drives a loose pinion 45 on the shaft of the padded 130

roll 6 and capable of being connected to drive said padded roll by operation of a clutch 46 similar to the clutches 39. Gear 42 also drives an intermediate pinion 47 on a stationary shaft 48 which in turn drives an intermediate pinion 49 journaled in a pressure lever 50, Fig. 3, said gear 49 driving a gear 49' on the shaft of the padded roll 4 and capable of being connected to drive said roller by manipulation of the clutch 51 similar to clutches 39.

At the right hand side of the machine the hot roll drive shaft 41 is provided with a gear 52 which drives a gear 53 fast on a gudgeon on the shaft of hot roll 5. Fast with the gear 53 is another gear 54 meshing with a driving gear 55 fast on the shaft of the hot roll 3.

The levers 44 and 50 which carry the padded rolls 4 and 6 are mounted to swing about their respective pivots 41 and 48 to enable the padded rolls to be moved relative to the heated ironing rolls, but true meshing relation of the driving gearing is maintained regardless of adjustment of said padded rollers.

All of the padded rollers are held to their co-operating ironing members, such as to the chest and hot rolls, by yielding pressure and the machine is preferably so constructed that all of said rolls can be applied with pressure either by power operation of the mechanism, or, if desired, by hand operated devices suitable for more delicate adjustment. The pressure applying and releasing mechanism is as follows:

At each side of the machine (see Fig. 5) is a longitudinally extending pressure bar 56 which may be of channel form in cross section, as shown in Fig. 17. These bars are provided with seats for pressure springs 57 bearing down upon seats on the pressure bearing members 31. The pressure of each spring may be regulated by the set screw 58 while the pressure bearing members 31 are held in place by the hanger bolts 59. Bars 56 are guided as to their vertical movement by rods 60 on the stationary frame passing through openings in said bars. Each end of each pressure bar 56 is connected by a link 61 to an eccentric strap 62 on one of a pair of cross shafts 63, so that by rotating said shafts in unison through approximately 180° or less, the rolls can be moved down toward the chest with uniform application of pressure over the full area of the chest or can be moved out of engagement therewith to protect the padding. The front end of each pressure bar 56, to wit, that end at the feeding end of the machine, or at the right in Fig. 3, also has a seat for a pressure spring 64 bearing upon a seat member 65 carried on one end of the lever 44, and each pressure bar has a pin 66 working in a slot 67 in member 65. Therefore, operation of

the bars 56 to apply the rolls 8 to the chest also applies the padded roller 6 to its co-operating heated roller 5.

Referring to Fig. 10, 68 represents one of a pair of levers, one at each side of the machine, each of said levers having one arm provided with a spring cup or seat 69 for a spring 70 effective upon the shaft of padded roll 4, the other arm of said lever being connected by a link 71 to an eccentric strap 72 upon one of the transverse pressure producing shafts 63. The two sets of levers 50, 68 at opposite sides of the machine are relatively rotatable about the shafts 48 so that actuation of the shaft 63 applies the padded roll 4 in unison with application of the other padded rolls 6, 8.

The operating mechanism for applying the rolls with pressure is as follows:

Referring to Fig. 7, the drive shaft 12 is provided at the left hand side of the machine with a gear 73 meshing with a gear 74 on a transverse shaft 75. Said shaft carries a loosely rotatable bevel gear 76 capable of being connected to be driven by shaft 75 by means of a slideable clutch member 77 actuated by a lever 78 having the usual clutch shifting yoke 79. Said lever slides in a guide formed by a transverse tie rod 80 and a bracket or support 81 adjacent thereto and is normally held in clutch open position by a tension spring 82. The bevel gear 76 drives a bevel gear 83 on a longitudinally extending shaft 84 provided with two worms 85 each of which actuates a worm gear 86. These worm gears are fast with the two transverse pressure controlling shafts 63 before referred to.

When the machine is idle the parts are adjusted so that the padded rolls are out of contact with the chest and heated ironing rollers, but when it is desired to operate the machine the operator closes the clutch 77 by operating handle 78 and utilizes the power of shaft 75 to turn the two shafts 63 in unison until said shafts have been rotated approximately 180° (more or less) to produce the proper pressure of the padded rollers on the chest and ironing rollers. The clutch is then opened and the machine operated for ironing. The same mechanism may be used for releasing the pressure.

Shaft 84 is preferably also provided at the feeding or operator's end of the machine with a hand wheel 87 suitable for use in adjusting the shaft 63 by hand for more delicate adjustment than might be secured with the power mechanism.

The several tie or hanger bolts 59 support the padded rollers or more accurately hold them as to their relation with the pressure bars 56 so that by proper adjustment of the screws 58 all of the rollers can be brought to the proper position relative to the pressure bars so that they will contact properly with

the chest. The first two padded rollers 8 at the feeding end of the machine, which are shown more particularly in Figs. 10 and 16, are however preferably provided with special adjusting means. As to these rollers, their hanger bolts 59 have heads 88 lying above swivel blocks 89 in which are pivoted eccentric cams 90 operated by handles 91 and bearing upon plates 92. By turning these cams to the position shown in Fig. 16, either or both of the first two padded rollers can be elevated against the pressure of its springs. This arrangement is useful when the collars contain a relatively great amount of moisture and enables the pressure at the first one or two rollers to be reduced or released so that the collar will readily travel beneath the first two rolls and along the chest without being subjected to such a great pressure as to form wrinkles therein or tend to make the collar stick to and travel around a roll. Also by reducing the pressure at these rollers the collar is preliminarily ironed or dried with maximum thickness and is not unnecessarily thinned as it is with higher pressure. After passing these first two rollers the heat of the chest has usually dried the collar sufficiently so that it will readily pass beneath the later rollers with full pressure thereon, and without being further thinned.

While the arrangement described enables the first two rolls to be raised to reduce the pressure thereof, it is of course obvious that one or even more than two of the rolls could be so arranged. Also when these adjustable rolls are lowered to their full pressure positions they operate in exactly the same manner as the other rolls and the full pressure of the springs is effective upon them. In the construction of these machines the springs are all carefully made and adjusted so that under full pressure the springs have a definite degree of yield and usually adjustment is made so that the degree of yield is the same for all of the rollers. This is useful in padding the rollers as the material is wound upon the rolls when they are down or in pressure position, the pressure of the springs being effective to pack the padding to the desired density. Therefore, the first two rolls on this machine can be padded in their down position just the same as all other rolls, but can also be raised to a reduced pressure position for the purposes before stated.

55. The ironing chest 7 is a hollow form, as shown in Fig. 6, and is mounted to have horizontal reciprocating motion from right to left and back again in Fig. 6. It is preferably supported on anti-friction members, such as rollers 93, to reduce the friction. The mechanism for reciprocating the chest is as follows:

Worm gear 30, before referred to, drives a worm 94 upon a stub shaft 95 which is provided with a pinion 96 on the outside of the

frame driving a gear 97 on a short shaft 98 which is connected by gears 99 (Fig. 7) to rotate a transverse shaft 100 mounted in suitable brackets on the frame. This shaft is provided at its opposite ends with crank 70 arms 101, each of which is connected by a rod 102 (Fig. 6) to a depending ear 103 on the chest. The reduction at the worm gearing produces constant but relatively slow rotative motion of the shaft 100, so that the effect is to slowly reciprocate the chest 7 while the work is being carried across the same by the effect of the padded rollers, or in other words while the chest and rollers are in co-operative ironing relation. The crank arms 80 are preferably of such length that the total travel of the chest is slightly greater than the distance between two successive rolls 8. Consequently every square inch of the chest is acted upon by the pressure of the rolls 8 and is therefore cleaned of any particles of starch which might tend to be deposited or to be collected therefrom.

Suitable means is preferably also provided for burnishing the collars or work, or, in other words, providing the same at least upon one surface, with a polish or high finish. The means shown in the present application comprises a padded roll 9 and heated burnishing rollers 10. These rollers 105 are driven by mechanism as follows:

Referring to Figs. 4, 5 and 7, drive shaft 12 is provided at its right hand end with a pinion 104 which drives a train of gears indicated generally at 105 (Fig. 4) the final one of which drives two gears 106, one on each of the shafts of the rolls 10. One gear 106 drives a gear 107 on a cross shaft 108, which, at the left hand side of the machine is provided with a gear 109 driving an intermediate gear 110 connected to operate a gear 111 on the shaft of the padded roll 9. Gear 110 is mounted on a stub shaft 112 at the joint between two links or levers 113 to enable the padded roller 9 to be adjusted vertically toward and away from the hot rolls 10 in substantially the same manner as the rolls 4 and 6 are adjusted but still maintaining driving connection and true meshing relation of the gearing. The hot rolls 10 rotate faster than the padded roll 9, say four times as fast, and thereby polish the collar surface and produce a high gloss or finish thereon.

The padded roll 9 is held down to its 120 heated rollers by the yielding pressure of springs 114 bearing upon blocks 115 and located in yokes 116 at the upper ends of the rods 117 (Figs. 18, 19 and 20), said rods being connected at their lower ends to straps 125 surrounding the eccentric 118 on a cross-shaft 119. Said shaft at its lower end is provided with an operating handle 120 having a spring pressed pin 121 adapted to enter any one of a series of openings 122 in 130

a segment 123, 124, Fig. 4, represents a stop lug against which the handle 120 abuts when the padded roll is raised to remove the pressure. By turning the handle 120 in the 5 counterclockwise direction, Fig. 4, shaft 119 is turned to actuate the eccentric 118 and move the padded roll down with increasing pressure into pressing engagement with the burnishing rollers. The stop pin 121 may 10 be entered into any one of the holes 122 to hold the parts in adjusted position.

125 represents a clutch similar to the clutches 39 for connecting the padded roller to be released or driven when desired.

15 Fig. 15 illustrates a section through one of the heated rolls and specifically through the left hand end of the roll 3. It illustrates the supply of heating medium, such as steam, for the hot roll 3, but it is understood that 20 heating may be supplied to all of the hot rolls 3, 5 and 10 in the same manner. As illustrated, steam supplied from a pipe 126 flows through a channel 127 to the chamber 128 in the roll from which it flows by way 25 of channel 129 to the outlet pipe 130, although the flow could be in the reverse direction if desired. 131 indicates the necessary stuffing box for permitting rotation of the roll relative to the steam supply pipe. 30 Steam for heating the chest is supplied from a pipe 132 from which it flows through stuffing boxes 133, 134, and 135 at the joints in the pipe connections 136, thence through 35 a supply pipe 137 to the chamber 138 in the chest and out through a pipe 139 to a similar series of stuffing boxes and pipe connections. This arrangement circulates a continuous supply of steam through the chest and at the same time enables it to move 40 back and forth as desired.

Fig. 17 indicates the pressure indicator, comprising a segment dial 140 provided with indicia 141 to co-operate with a pointer or indicator 142 pivoted at 143 and an arm of 45 which is connected by a link 144 to a portion of the stationary frame 145. The dial is carried by one of the pressure bars 56 and as said pressure bar moves up and down the indicator travels over the dial and indicates 50 to the operator the pressure under which the machine is operating.

Referring to Fig. 6, 146, 147, and 148 indicate a series of strippers or doffer knives located respectively at the padded rolls 4, ironing roller 5 and the last roller 10. These doffer knives perform the usual function of stripping the work from one set of rolls when it tends to cling thereto and guiding it to the next.

60 The machine is operated by connecting up the drive and applying the several padded rollers with pressure to their ironing members. The collars or other articles to be ironed are laid upon a feeding table 149 at the entrance to the machine and introduced

between the first rollers 3, 4. Roll or turn down collars are introduced to the machine with the outer surface of the flap and inner surface of the band down. The first two pairs of rollers 3, 4, and 5, 6 produce a 70 preliminary pressing effect which is desirable when the collars are particularly moist but which in any event is accomplished by rolls as distinguished from a chest along which the material slides. Each surface of the collar passes over a heated ironing roller so that both sides are preliminarily treated in the same way. The collar then passes along the surface of the ironing chest and is advanced by the effect of the padded 75 rollers. The first two of these padded rollers may be adjusted to give a reduced pressure when thickness is a desirable quality in the finished work or when the collars are specially moist, so that they will pass said rolls without the formation of wrinkles and will be sufficiently dried so that the later rollers 80 can operate with full pressure. While passing the several rollers the collar is straightened by the increasing peripheral speed to further assist in avoiding wrinkles. Finally the collar is subjected to the effect of burnishing rollers 10 which rotate at relatively 85 high speed and produce a smooth finish, although, if desired, these rollers 10 may be grooved or otherwise roughened or have any desired kind of polishing surface. When a special finish is not desired the padded roller 9 can be adjusted out of contact with the burnishing rollers 10 without 90 effect upon any other part of the machine, in which case the collars travel idly over the rollers 10 and are discharged over the doffer knife 148 to the receiving bin 150. In other words, the machine can be operated 95 either with or without the burnishing rollers.

What I claim is:

1. An ironing machine, comprising a chest having an ironing surface, a series of pressure rollers co-operating with and spaced at intervals along the ironing surface of said chest, means for causing said rollers to rotate at varying peripheral speeds, the peripheral speed of each succeeding roller being greater than that of the preceding roller, and means for producing relative reciprocation between said chest and said pressure rollers along the line of movement of the work along the chest.

2. An ironing machine, comprising a chest having a flat ironing surface, a series of pressure rollers co-operating with and spaced at intervals along the chest, the diameter of each succeeding roller being greater than that of the preceding roller, and means for producing relative reciprocation between said chest and rollers along the line of movement of the work along the chest.

3. An ironing machine, comprising a chest, a plurality of ironing rollers, adjust-

able yielding means for applying said rollers to the chest with any desired ironing pressure, and means independent of said yielding means for relieving the pressure of one roller upon the chest without disturbing the adjustment of said adjustable means.

4. An ironing machine, comprising a chest, a plurality of ironing rollers, operating means for moving said rollers as a gang into and out of ironing position, adjustable yielding means for applying said rollers when in ironing position to the chest with any desired ironing pressure, and means independent of said operating means and of said yielding means for relieving the pressure of one roller upon the chest without disturbing the adjustment of said adjustable yielding means.

5. An ironing machine, comprising a chest, a plurality of ironing rollers, adjustable yielding means for applying said rollers to the chest with any desired ironing pressure, means independent of said yielding means for relieving the pressure of one roller upon the chest without disturbing the adjustment of said adjustable yielding means.

6. An ironing machine, comprising a

chest, a plurality of ironing rollers, operating means for moving said rollers as a gang into and out of ironing position, adjustable yielding means for applying said rollers when in ironing position to the chest with any desired ironing pressure, means independent of said operating means and of said yielding means for relieving the pressure of one roller upon the chest without disturbing the adjustment of said adjustable yielding means, and means for producing relative reciprocatory movement of said chest and rollers along the line of motion of the work along the chest while the chest and rollers are in cooperative ironing relation.

7. An ironing machine, comprising a chest, a series of co-operating pressure rollers, a pair of co-operating rollers effective for producing an ironing operation upon the work before it reaches the chest, and means for simultaneously adjusting the chest rollers relative to the chest and one of said co-operating rollers relative to the other.

8. An ironing machine, comprising an ironing chest, co-operating pressure rollers, and burnishing rollers also effective upon the work before leaving said machine, said burnishing rollers being arranged on the same side of the work as the ironing chest.

In testimony whereof I hereby affix my signature.

CHARLES E. WAREAM.
